UNITED STATES PATENT OFFICE.

WILLIAM ARTER, OF WORCESTER, MASSACHUSETTS.

GRINDING MACHINE.

Application filed September 6, 1921. Serial No. 498,658.

To all whom it may concern:

Be it known that I, WILLIAM ARTER, a subject of the King of Great Britain, residing at Worcester, in the county of Worcester and State of Massachusetts, have invented certain new and useful Improvements in Grinding Machines, of which the following is a specification.

This invention relates to grinding machines and more particularly to such machines of the type in which the grinding tool is given a reciprocatory movement while the article to be ground is held in a relatively fixed position. The invention is especially concerned with machines for automatically grinding the faces of piston rings and similar articles.

Machines of this character, as heretofore constructed, generally have cam operated motions or other mechanisms equally inherently slow of action which impedes production. Accordingly an object of the present invention is to overcome this difficulty, and to this end a feature of the invention comprises improved actuating mechanism which will produce practically instantaneous movement of the necessary parts.

A further object of the invention is to provide improved mechanism for feeding the work to the grinding wheel and discharging it after having been ground, thus rendering the machine entirely automatic in its action.

To the accomplishment of these objects and others which will hereinafter appear and which will readily be understood by those skilled in the art, the invention comprises the features and combinations of parts hereinafter described and then particularly pointed out in the appended claims.

The invention is best illustrated in the accompanying drawings, in which—

Figure 1 is a view in front elevation of a machine for automatically grinding piston rings and like articles;

Fig. 2 is a view in end elevation of a portion of the machine shown in Fig. 1;

Fig. 3 is a view, in plan, of the chuck and adjacent parts including the piston ring carrier;

Fig. 4 is a vertical, sectional view on the line 4—4 of Fig. 2;

Fig. 5 is a longitudinal, sectional view through the line 5—5, of Fig. 4;

Fig. 6 is a view of the air cylinder, in plan, showing the cushioning valve in section;

Fig. 7 is a view, in end elevation, of the air cylinder showing the cushioning valve in position;

Fig. 8 is a partial, longitudinal section of the air cylinder showing the cushioning valve and seating plug;

Fig. 9 is a section through a piston locating ring in place on the rotating carrier plate;

Fig. 10 is a section similar to Fig. 9 showing a replaceable piston locating ring in position to be assembled with the carrier plate;

Fig. 11 is a detail in plan, and partly in section, of the ring carrier indexing mechanism;

Figs. 12 and 13 are views showing a modified form of ring carrier indexing mechanism permitting more than one grinding operation on each ring, Fig. 12 being a horizontal section on the line 12—12 of Fig. 13;

Figs. 14, 15 and 16 are elevational views of another modified ring carrier indexing mechanism, similar to that shown in Figs. 1 and 2 except that it is mechanically operated from the reciprocating wheel head;

Figs. 17 and 18 are a plan and diametric section, respectively, of a modified form of locating ring for use on the ring carrier;

Fig. 19 is a view in elevation of portions of a machine in which the grinding wheel head and the ring carrier indexing mechanism are actuated by oil pressure;

Fig. 20 is a sectional detail of the oil valve used in the machine shown in Fig. 19; and

Fig. 21 is a part vertical sectional view through line 21, Fig. 5 showing modified arrangement of valve when oil operated.

In the embodiment of the invention illustrated in the drawings is included a well known type of grinding machine employing a magnetic chuck to hold and rotate the work, and a reciprocating head carrying a rotary grinding wheel which traverses the work held in the chuck.

Since the machine shown is designed particularly for facing piston rings, a magazine is provided to hold a quantity of the rings, and they are separated one at a time from the stack by a rotary ring carrier and trans-

- ferred to a position over the chuck and beneath the path of travel of the grinding wheel. An indexing mechanism for the carrier is employed which, in the form illustrated in Figs. 1 to 11, provides for only a single reciprocation of the grinding wheel across each piston ring after which it is carried away from the wheel and discharged. In the form illustrated in Figs. 12 and 13 10 the indexing mechanism for the ring carrier is so designed that each ring may be caused to remain in the chuck for two reciprocations of the grinding wheel, or more than two, as may be required for the work in hand. Both of these mechanisms are illustrated as being driven by fluid pressure but in the form of the invention illustrated in Figs. 14, 15 and 16 the indexing of the ring carrier is effected through mechanical devices actuated, as before, from the reciprocation of the grinding wheel head. The principle of operation is the same in each form. In the form of the invention shown in Figs. 19 and 20 the principle of operation 20 also is the same except that a hydraulic drive is employed, controlled also by the reciprocation of the wheel head.
- Having indicated the principle upon which the illustrated machine operates, a detailed description of its various features will now be given, it being understood that the main constructional features, such as the grinding wheel head and magnetic chuck with their power actuating mechanism and related parts of the construction, are fully disclosed in the prior United States Letters Patent to White No. 1,184,905 dated May 30, 1916, and Arter No. 1,357,924 dated November 2, 1920.
- 40 The improved mechanism shown in the accompanying drawings comprises a rotary magnetic chuck 21 (Fig. 3) acting as a holder for the work, shown as a piston ring R. A bracket 23 surrounds the chuck 21, the function of which is to protect the chuck shaft bearings and to form a support for the main bracket 24, to which it is fastened by bolts 25 (Fig. 2) and is made adjustable thereon by means of a sliding key and elongated slots 26. To make this adjustment a screw 27 is threaded into the upper end of the bracket 24. This screw has an apertured head 28 to provide means for turning it, which fits into a slot 30 (Fig. 3) in the bracket 23. It will be seen that when the bolts 25 are loosened and the screw 27 is rotated, the whole bracket 24 and all parts thereon will move up or down according to the direction of rotation. The parts now 50 to be described may thus be properly positioned according to the vertical adjustment of the chuck.
- In a vertical hub 31 on the bracket 24 a spindle 32 is mounted and carries a horizontal disc 33 at its upper end, preferably of

non-magnetic material, and having a series of circular holes 34 equally spaced in about its margin. This disc acts as a carrier for the piston rings R which are to be ground. The holes 34 are provided with annular locating rings or bushings 35, preferably of hardened steel, which have different interior diameters and are replaceable for various sizes of piston rings.

Each locating ring or bushing 35 may be 75 made as shown in Figs. 9 and 10 with a V-cut in its edge fitting into a complementary shape in the edge of the hole 34 in which it is to be seated. In order to assemble the rings without splitting them, the lower part 80 of the V-cut in the ring is removed at four places, each length so removed approximating one-eighth of the circumference. Also the whole of the V-cut in the hole 34 is similarly removed in four places, each 85 length so removed approximating a little more than one-eighth of the circumference (see Fig. 3). It will be seen that when the ring 35 is superimposed on the hole 34, as in Fig. 10, with the cut-away portions of the 90 ring above the uncut-away portions of the hole, the ring will be permitted to drop into such position that its upper face and that of the plate 33 will be flush. A one-eighth turn of the ring will bring the uncut portions of the ring and the hole into engagement, preventing the ring from moving up or down, without turning it back again. To hold these rings in position, there is provided a series of slidable locking plates or 95 dogs 36 (Fig. 3) held in slots in the disc 33 and secured thereto by screws.

The indexing mechanism for the carrier 33 comprises a gear wheel 38, Fig. 2, mounted on the spindle 32, but free to rotate relatively thereto, and to which is rigidly fastened a cam 39, (Fig. 11). Engaged with the gear 38 is a piston rod 40 (Figs. 1 and 5) having teeth 37 cut in it for this purpose. The piston rod is guided in a housing 401 formed by a depending bracket and is connected to a piston 41 in a double acting fluid cylinder 42 which is rigidly held to the bracket 24 by bolts, as shown in Fig. 2. The cam 39 (Fig. 11) has a boss 65 to which is pivoted a pawl 66 engaging a toothed disc or ratchet wheel 67 rigidly fastened to the shaft 32. It will be seen that when the piston rod 40 moves in one direction, thus rotating the gear 38 and cam 39, the pawl 66 is caused to rotate the disc 67 and the shaft in one direction; but when the piston rod 40 moves in the opposite direction no movement of the spindle 32 takes place because the pawl 66 rides over the teeth on the disc 67 without moving it. The spindle 32 and all parts rigidly attached thereto has, therefore, a periodic movement in one direction only.

In order to hold the carrier stationary

after it has been indexed, the spindle 32 has rigidly secured to it a circular plate 77 (Fig. 11) with notches 78 cut in its periphery corresponding in number and angular spacing to the holes 34 in the carrier plate 33. A plunger bar 79 has its end shaped to fit into these notches 78 and when so positioned holds the carrier plate 33 against movement. The plunger bar, preferably of rectangular section, slides in a bracket 80 bolted rigidly to the plate 24 and is backed up by a spring 82 which always tends to hold the plunger 79 in engagement with the disc 77. A roller 83 is attached to the plunger 79 and is located in the path of the cam 39, so that when the high part 84 of the cam engages the roller the plunger is pushed out of its engagement with a notch in the disc 77 and the carrier plate 33 may then be moved by the pawl and ratchet mechanism.

The air, or other operating fluid, in the cylinder 42 is controlled by a valve slide 44, Figs. 4 and 5, having D-shaped ports 45 and 46, and operating between the cylinder and a wear plate 43, made to seat by springs 431, and held down by a cover 432. Air, or other fluid, under pressure is conducted by pipe connections directly to the center port hole 47 of the cylinder 42. In the position shown in Figs. 4 and 5 air is being admitted to the left port hole 48, thence by a duct in the cylinder head 54 to the rear of the piston 41, thereby pushing the piston rod out while the piston rod end of the cylinder is open to the atmosphere through the port 46. Shifting the valve to the left obviously results in reversing the movement of the piston.

Under working conditions, when one side of the cylinder is quickly opened to exhaust and compressed air admitted to the other end, the resistance to motion is so small and the momentum in the moving mass is so great that it is very difficult to control an accurate positioning of the piston ring carrying disc 33; also under such a condition it is impossible to prevent piston rings being broken in the magazine, presently to be referred to, due to the hard sharp blows they receive when dropped into position within the locating rings 35. To remedy this it is proposed to control both the inlet and the outlet of the piston rod end of the cylinder, as shown in Figs. 6, 7 and 8. For this purpose a plug 49 is introduced into the drilled hole 50 leading to the port 51. Through this plug a small hole 52 of a definite size is drilled, sufficient to allow enough air to pass through, and thence through the duct 243, to move the piston rod back on its idle stroke without undue jar. In this stroke there is practically no work being done by the piston except moving the gear 38 and the cam 39

and consequently there is very little moving mass to acquire momentum and cause jar. On the outward or working stroke of the piston rod, however, when the momentum of the moving parts is great, it is found absolutely necessary to control the speed of the piston, making it as uniform as possible. This is accomplished by controlling the rate of exhaust by means of what may be called a cushioning valve 53, introduced loosely between a shoulder formed by the cylinder head 54 and the plug 49. This valve 53 has a small hole 55 drilled and chamfered in the center, the diameter of which is determined by the desired travelling speed of the piston ring carrier 33. It will be seen that any exhaust from the piston rod end of the cylinder must come through the drilled hole 55, forcing the cushioning valve 53 against the plug 49, partially closing the hole therein and leaving only the small exit in the valve 53 for exhausting. This obviously can be reduced to meet any conditions produced by varying air pressures, and its effectiveness is such that it is possible to control the speed of the moving mass to practically any limit. Peripheral grooves, as shown, provide suitable intake ports through this valve. The position of the valve 53, as shown in Figs. 6 and 7, is the most convenient for inspection but its location in any place in the exhaust circuit would give the desired results.

The valve slide 44 is operated by means of the dogs 56 and 57 (Fig. 1) which operate the reversing mechanism of the grinding machine, and they are adjustably mounted on the wheel head 58 as fully explained in the White Patent No. 1,184,905. The dogs alternately engage a lever 59, rigidly fastened to a rock shaft 60, at opposite ends of the stroke of the wheel head 58. The slight movement of the lever 59 makes it practically instantaneous, and this movement is transmitted through a lever 62 to a valve rod or link 61, both mounted at the rear of the machine, thus operating the valve slide 44 to which the link is attached by a pin 64 (Fig. 4). This operation admits air to the piston 41, which operates the piston rod 40 and the gear 38 at either end of the stroke of the wheel head 58. The advantage of using the automatic reversing dogs 56, 57, may be seen by the fact that it is practically impossible to have the valve slide 44 in the wrong position when thus governed.

Mounted on the bracket 24 is a magazine plate 68 (Figs. 2 and 3), in which a hole 72 is cut large enough to accommodate the largest piston ring within the scope of the machine. A number of vertical bars or rods 69, preferably four, of any desired length are adjustably mounted vertically in relatively adjustable brackets 70 dovetailed into

slots 71 diagonally cut across the hole 72 in the plate 68. These rods form the magazine for holding the stack of piston rings. It will be seen that by means of the elongated slots 73 in the brackets 70, the bars 69 may be adjusted toward and from the center of the hole 72 to enable the magazine to hold different sizes of piston rings. The brackets 70 are held in adjusted position by 10 screws, as shown in Figs. 2 and 3. The vertical adjustment of the bars 69 is secured through set screws 63 (Fig. 2). For the best operating conditions, the bars 69 are preferably located as near to the top of the 15 carrier plate 33 as the thickness of the piston rings R will allow, hence, the reason for having the bars 69 vertically adjustable.

A receiving plate 74, the upper face of which is practically flush with the face of 20 the work holding chuck 21, projects under the carrier plate 33, the latter traveling between the two plates 68 and 74. Two thickness pieces 75 and 76, Fig. 2, provide means for adjusting the relative distances between 25 the bracket 24, the receiving plate 74, and the magazine plate 68.

In Fig. 3 of the drawings, six equi-distant piston ring receiving holes 34 are shown in the carrier plate 33 but any practical number 30 may be employed. These holes are so spaced that when the plate 33 is at rest, one hole 34 is located directly in the center of the hole 72, while another hole is directly over the center of the chuck 21; and these two 35 holes are located in adjoining positions so as to have the least possible distance to carry the work.

The operation of the parts thus far described is as follows:

40 The piston rings R to be ground are stacked between the four magazine bars 69, the bottom ring resting on the receiving plate 74 and inside the locating ring 35 in the plate 33, the size of which has been pre-
45 selected to fit the size of the piston ring which is to be faced. When the grinding wheel G is reaching its extreme backward position away from the ring, the current energizing the rotary magnetic chuck or
50 work holder is automatically switched off, as fully explained in the Arter Patent No. 1,357,924, releasing the ring on the chuck. Immediately this release is made the dog 56 moves the valve slide 44, by means of the
55 levers 59 and 62 and the rod 61, thereby admitting air into the rear end of the cylinder 42, causing the piston rod 40 to move outward, or to the right in Figs. 3 and 5, thus rotating the gear 38 and the spindle 32
60 through the engagement of the pawl 66 with the ratchet wheel 67. This rotates the carrier plate 33, and the piston ring resting on the receiving plate 74 is simultaneously carried to the center of the magnetic chuck.
65 Likewise the piston ring resting on the

chuck is removed therefrom at the same time. The finished rings as they are carried away from the chuck drop from the carrier on an unloading plate 85 (Fig. 2), which may be provided with a gravity chute 86 to transfer them to a convenient receptacle or stacking device, such as that shown at S in Figs. 2 and 3.

When the grinding wheel G starts on its forward stroke, the rotary magnetic chuck 75 is automatically energized before the wheel touches the piston ring, this energizing effect being continued until the wheel has returned to the same position on the backward stroke. As the grinding wheel reaches its furthest 80 position towards the center of the piston ring, the dog 57 moves the lever 59 in an opposite direction so that the valve slide 44 makes an air connection to the opposite end of the cylinder 42 and the piston rod 40 is 85 drawn in. When the piston rod 40 is drawn in, the gear 38 and the cam 39 being free on the shaft 32, are rotated backward, carrying the pawl 66 with them, without rotating the disc 67. There may be a certain amount of 90 friction between the pawl and disc while it is riding back, tending to move the disc slightly, but this may be taken care of by an automatic brake of any convenient form applied to the carrier 33. Such a brake is shown at 95 223, Fig. 3.

It may be noted that a hole is drilled and tapped in the cam 39, in which may be screwed a handle 88, Fig. 11. This provides 100 means to operate the piston ring carrier 33 by hand, in case there should be a break down in the air plant.

Means also is provided to clean the chuck of grit, preferably consisting of an air cleaner nozzle 89 (Fig. 3), through which air under pressure is forced carrying the flying grit to a receiving cone of usual form in which a suction is maintained.

Thus far the description relates to a mode of operation in which the work is removed after one forward and one backward movement of the grinding wheel head 58. It may, however, be necessary to make two or more cuts by the wheel G before removing the work. This may be accomplished by the modified construction shown in Figs. 12 and 13. In this construction the gear wheel 90 is rigidly attached to the ratchet wheel 67, but both are free on the spindle 32. The gear 90 drives a pinion 91, rigidly attached to an intermittent pinion gear 92, both being free to rotate on a pin 93 screwed into an adjustable bracket 94. The pinion 92 drives an intermittent gear wheel 95 (Fig. 12) which is keyed, together with the locking plate 77, to the shaft 32. It will be seen that the ratchet wheel 67 can be moved forward by the pawl 66 without moving the gear 95, except when the teeth of the pinion 92 are in engagement with the teeth of the gear 95.

The number of reciprocations made by the piston rod 40 for each advancing movement of the carrier 33 thus are predetermined by the ratio of the gearing. The intermittent ratio between the gears 92 and 95 may be made as desired, and by employing a series of gears 95 and a series of cooperating pinions 92, such that sliding keys would engage any pair, operative to drive the shaft 32, it would be possible to select, at will, any desired number of cuts to be given the work before removing it. The same general results can also be secured by removing one pair of gears 92 and 93, replacing them by another pair having the desired ratio.

The air driven mechanism for operating the carrier plate 33 has been particularly described on account of its flexibility, quickness and ease of movement. Similar results could be obtained by using any other fluid or by an electric motor or solenoid magnet with switch controlled by the wheel head. Where, however, there is no air pressure available, and it is necessary to effect this movement mechanically, the mechanism shown in Figs. 14, 15 and 16 may be used.

Instead of the air cylinder piston 40, a similar toothed rod 400 is arranged to operate parallel to the front of the machine. This rod is pivotally coupled to a link 96 which is connected to a lever 97 pivoted on a stud 98 on the frame and having at its upper end two square-shanked studs 99 and 100 engaging alternately with pawls 101 and 102 pivot-35 ed on brackets 103 and 104 fastened to the machine frame. Directly in front of the lever 97, and pivoted on the same stud 98, are the two separate levers 106 and 107 connected together by a spring 108 which has an initial tension in it so that the levers 106 and 107 always tend to come together. Pivoted on the stud 98 is also a lever 109 directly placed in front of the levers 106 and 107. Projecting from the lever 109 at its upper 40 end is a pin 110 placed so as to be engaged alternately by the dogs 56' and 57' like the dogs 56 and 57, respectively, and mounted in the same manner on the wheel head 58. Just below the pin 110 in the lever 109 is a 50 pin 111 to engage the pawls 101 and 102. At the lower end of the lever 109 is a pin 112 so located as to engage the levers 106 and 107. In the lever 97 is another pin 113 placed to engage the levers 106 and 107.

In Fig. 15 the grinding wheel head 58 has just reached its extreme position toward the center of the piston ring which is being ground, the dog 57' as pushed over the lever 108 by its engagement with the pin 110 so that the pawl 102 is lifted by the pin 111 nearly out of engagement with the stud 100. The lever 97 is therefore in a position from whence it may instantly be moved over to a position parallel to that of the lever 109. The action of the dog 57' on the lever

109 moves the lever 106 outward by means of the pin 112, increasing the tension in the spring 108, and transmitting this tension to the lever 107. This pressure is transmitted to the lever 97 through the pin 113, but until 70 the pawl 102 releases the stud 100 no movement of the lever 97 can take place. Directly, however, the stud 100 is released a practically instantaneous movement of the lever 97 occurs, which movement is transmitted to the toothed rod 400. The gear 38 is thus rotated but without moving the carrier disc 33. The action on the reverse stroke of the wheel head 58 is exactly like that just described except that in this latter 80 case the carrier 33 is moved one-sixth of a revolution by the pawl 66 acting on the toothed disc 67. In this mechanism advantage is taken of the full movement of the dogs 56' and 57', thus gradually tensioning 85 the spring 108 and storing up the energy for the movement of the gear 38 at the end of each stroke of the wheel head 58. The disc 77 is released and locked by the cam 39 and plunger 79 as heretofore described.

In Figs. 17 and 18 a modified, and preferred, form of locating ring for the carrier 33 is illustrated. These rings 120 are of annular form and may present varying internal diameters for receiving piston rings of different sizes. The external diameter is the same as that of the holes 34 in the ring carrier and the edges of both the holes 34 and the rings 120 are threaded, so that they may be quickly screwed into place by inserting a spanner in the holes 121 provided for this purpose. The locating rings 120 are provided with a series of peripheral notches 122 with one of which the locking dog 36 (Fig. 3) at each hole 34 cooperates to hold the ring against rotation. A plurality of notches 122 are provided to insure a seating of the ring flush with the upper surface of the ring carrier 34. The locating ring 120 is simpler in construction than the ring 35 hereinbefore described and is equally effective.

In Figs. 19 and 20 a control of both the wheel head reciprocation and the indexing movement of the piston ring carrier by oil or other hydraulic pressure is illustrated. An oil tank 125 is provided to which is connected a rotary pump 126 driven by a belt running on a pulley 127. Oil is forced by the pump through the pipe section 128, to the lower port of a directing valve 131. The plug 132 of this valve is rotated within the valve casting by movements of the lever 59 operated through impacts from the dogs 56 and 57 on the wheel head. Two diametrically opposite horizontal ports of the valve 131 have connecting pipes 133 and 134 leading to each end of a cylinder within which is a double acting piston operating a piston rod 136 connected to a lug 137 depending from the wheel head. An upper vertical port of

the valve 131 as a discharge pipe 138 connecting it with the tank 125. In Figs. 19 and 20 the wheel head is about to end its forward movement, the handle 59 being at such an angle that the port 139 of the valve is connected, through the plug port 140, with the pipe 134. Passage of the oil through the pipe 134 forces the piston to the left (Fig. 19) and the contained oil in the cylinder discharges through the pipe 133, plug port 141 and circular port 142 to the pipe 138 and thence to the tank. When the dog 57 meets the lever 59 at about the end of the forward movement of the wheel head the plug 132 is rotated to bring its ports 140 and 141 into the dotted line position shown in Fig. 20 and the direction of movement of the piston is immediately reversed, as will be understood from the foregoing description. The reciprocation of the wheel head is thus automatically continued whenever the inlet pipe 128 is open. This is controlled by a valve 143 conveniently placed near the pump, which also regulates the rate of flow and consequently the speed of rotation.

In this form of the invention it is proposed also to control the ring carrier indexing mechanism by oil pressure. To this end a branch 144 from the inlet pipe 128 is provided, which leads to the inlet port 47 of the cylinder 42 shown in Figs. 4 and 5. The same mechanism for operating the valve slide 44 from the lever 59, as is shown in Fig. 1, can be employed and pipes 145 and 146 lead from the outlet ports at each side of the cylinder to a pipe 147 which joins the return pipe 138. In this construction the face on which the valve 44 slides is widened, as shown in Fig. 21, to take two outside ports with which the pipes 145 and 146, respectively, communicate. With these connections the piston rod 40 for operating the ring carrier indexing mechanism is actuated from the traveling head, as before, but by oil instead of air.

It is also contemplated that both the magnetic chuck which holds the piston rings, and also the grinding wheel, may be driven by turbines operated by fluid pressure, and this arrangement is particularly advantageous when the wheel head and the indexing mechanism are operated by hydraulic mechanism. It will be understood further, that some of the features of the invention are useful in grinding machines of the type where the work is reciprocated, instead of rotated, with relation to a rotating grinding wheel.

Nothing herein contained is to be interpreted as limiting the invention in the scope of its application to use in connection with the particular machine, or the particular modes of operation, or both, selected for the purpose of illustration and explanation. While the particulars of construction herein

set forth are well suited to the various forms of the invention disclosed, the invention is not limited to these details of construction nor to the conjoint use of all its features, nor is it to be understood that these particulars are essential since they may be variously modified within the skill of the artisan without departing from the true scope of the actual invention, characterizing features of which are set forth in the following claims by the intentional use of generic terms and expressions inclusive of various modifications.

What is claimed as new is:

1. A grinding machine of the character described having, in combination, a work holder, a grinding tool, said holder and tool being relatively rotatable, mechanism for the combined delivery of the articles to be ground to and their removal from said holder, and fluid pressure means for actuating said mechanism.

2. A grinding machine of the character described having, in combination, a work holder, a grinding tool, means to move the tool over the articles to be ground, a work carrier for delivering articles to and removing them from the work holder, and means controlled by the tool movement for operating said work carrier.

3. A grinding machine of the character described having, in combination, a work holder, a reciprocating grinding tool head, a rotary work carrier for holding a plurality of articles to be ground and successively delivering them to and removing them from the work holder, and means controlled by the later portion of the stroke of said head for intermittently rotating said work carrier.

4. A grinding machine of the character described having, in combination, a grinding wheel, a wheel head mounted for reciprocating movement to traverse said wheel over the work, a work holder, a work carrier for delivering articles to be ground to said holder and removing them from said holder, a fluid pressure mechanism for operating said carrier, and connections between said mechanism and said wheel head for controlling the operation of said carrier in accordance with the movements of said wheel head.

5. A grinding machine of the character described having, in combination, a work holder, a rotary work carrier adapted to receive a plurality of articles to be ground and move each article in a path over said holder, fluid pressure mechanism for indexing said carrier step by step to deliver articles to said holder, and means for supplying said carrier with articles during periods of rest thereof.

6. A grinding machine of the character described having, in combination, a work

- holder, a grinding tool, an intermittently movable work carrier for transferring articles to be ground to the holder, means for traversing said tool over the holder, and fluid pressure mechanism connected with said means to be actuated thereby for operating the work carrier.
7. In a grinding machine of the type in which a work carrier and a tool are both relatively movable, a double acting fluid pressure operated piston for moving one of said parts, and means operated by the movement of the other part for controlling the delivery of fluid to said piston.
- 10 8. A grinding machine having, in combination, a movable tool head, a movable work carrier for presenting articles to the tool, fluid pressure mechanism for operating one of said parts, mechanical means for operating said other part, and interconnected mechanism for controlling the movement of one part from the other.
- 15 9. A grinding machine having, in combination, a movable tool head, a movable work carrier for presenting articles to the tool, fluid pressure mechanism for operating said work carrier, mechanical means for operating said tool head, and means on the tool head for timing the effective operation of said fluid pressure mechanism.
- 20 10. A grinding machine having, in combination, a grinding wheel, a reciprocating wheel head supporting said wheel, a holder for supporting work for the operation thereof on of said wheel, an intermittently rotatable carrier for presenting articles of work successively to said holder, fluid pressure operating means for rotating said work carrier, and controlling mechanism for said fluid pressure means arranged to be actuated by said wheel head.
- 25 11. A grinding machine having, in combination, a work holder, a reciprocatory tool head carrying a grinding tool, a work carrier for transferring articles to be ground to said holder, means for intermittently moving said carrier, and means for reciprocating said tool head a plurality of times during each period of rest of the carrier.
- 30 12. A grinding machine having, in combination, a work holder, a reciprocatory tool head carrying a grinding tool, a work carrier for transferring articles to be ground to said holder, means for reciprocating said tool head to cause the tool to traverse an article delivered to the holder, and means controlled by said tool head movement for intermittently moving the carrier, including mechanism permitting a plurality of traverses of the head between each effective movement of the carrier.
- 35 13. A grinding machine, having, in combination, a work holder, a reciprocatory tool head carrying a grinding tool, a work carrier for transferring articles to be ground to said holder, means for reciprocating said head to cause the tool to traverse an article delivered to the holder, means controlled by said tool head movement for intermittently moving the carrier, and means for rendering certain traverses of said head ineffective to move the carrier.
- 40 14. A grinding machine having, in combination, a work holder, a reciprocatory tool head carrying a grinding tool, a work carrier for transferring articles to be ground to said holder, means for reciprocating said head to cause the tool to traverse an article delivered to the holder, means controlled by said tool head movement for intermittently moving the carrier, and means for utilizing preselected reciprocations of said head in regular series for effecting movements of the work carrier.
- 45 15. A grinding machine having, in combination, a work holder, a work carrier, and means to impart an intermittent movement to the carrier to successively transfer articles to be ground to the holder comprising fluid pressure mechanism including a double acting piston having its piston rod operatively connected to said carrier, a cylinder for said piston having an inlet and outlet port, and means in the fluid circuit for retarding the flow of fluid through said port in one direction only.
- 50 16. A grinding machine having, in combination, a work holder, a work carrier, fluid pressure means for moving the carrier to transfer articles to be ground to the holder, said means including a cylinder and a piston working therein and means in the fluid circuit for controlling the rate of exhaust of the fluid from said cylinder.
- 55 17. A grinding machine having, in combination, a work holder, a work carrier, a fluid pressure means for moving the carrier to transfer articles to be ground to the holder, and means in the fluid circuit for controlling the rate of exhaust of the fluid, comprising a cushioning valve providing a suitable intake port but movable by the exhaust to greatly reduce the size of the opening forming said port.
- 60 18. A grinding machine having, in combination, a work holder, a work carrier, a fluid pressure means for moving the carrier to transfer articles to be ground to the holder, and means in the fluid circuit for controlling the rate of exhaust of the fluid, comprising a valve seated for sliding movement in the fluid conduit, constructed to provide an adequate intake port when in one position and a restricted exhaust port when in another position.
- 65 19. A grinding machine having, in combination, a work holder, a work carrier, a fluid pressure means for moving the carrier to transfer articles to be ground to the holder, said means including a cylinder and

a piston therein and means in the fluid circuit for controlling the rate of exhaust of the fluid from said cylinder, comprising a valve movable to one position by the intake 5 pressure permitting free inlet of the fluid and to another position by the exhaust pressure providing a restricted exhaust of the fluid.

20. A grinding machine having, in combination, a grinding wheel, an intermittently movable piston ring carrier having a circular ring holding pocket of a diameter to receive the largest ring to be ground, and provided with circumferential means for receiving and removably holding an annular locating ring having an interior diameter to fit the piston ring to be ground, said locating ring also having circumferential means to cooperate in locking engagement with said 15 carrier means, and means for successively supplying said pocket with piston rings and driving the carrier to successively transfer said rings to the grinding wheel.

21. In a grinding machine of the type in which piston rings or the like are successively presented to the grinding wheel by means of an intermittently rotatable carrier having a plurality of circular pockets for receiving the rings, means for locating piston rings of 25 different diameters in said pockets comprising replaceable annular locating rings having the same exterior diameter as the pockets but varying interior diameters, and means cooperating both with said rings and 30 the carrier for locking any one of a series of said locating rings in one of said pockets flush with the surface of the carrier.

22. In a grinding machine of the type in which piston rings or the like are successively presented to the grinding wheel by means of an intermittently rotatable carrier having a plurality of circular pockets for receiving the rings, means for locating piston rings of different diameters in said 40 pockets comprising replaceable annular locating rings having the same exterior diameter as the pockets but varying interior diameters, and means on said locating rings and pockets for locking said rings to the carrier by a rotative movement of the ring 45 relative to its receiving pocket.

23. In a grinding machine of the type in which piston rings or the like are successively presented to the grinding wheel, an intermittently rotatable carrier having a plurality of circular pockets for receiving the rings, means for locating piston rings of different diameters in said pockets comprising replaceable annular locating rings having the same exterior diameter as the pockets but varying interior diameters, said ring 55 holding pockets each being provided with circumferential means for receiving and holding one of said locating rings flush with the surface of the carrier, each of said lo-

cating rings also having circumferential means to cooperate in locking engagement with said carrier means, and means at each pocket for holding the locating ring therein against rotation.

70

24. In a grinding machine of the type in which piston rings or the like are successively presented to the grinding wheel, an intermittently rotatable carrier having a plurality of circular pockets for receiving the rings, means for locating piston rings of different diameters in said pockets comprising replaceable annular locating rings having the same exterior diameter as the pockets but varying interior diameters, said ring holding pockets each being provided with circumferential means for receiving and holding one of said locating rings flush with the surface of the carrier, each of said locating rings also having circumferential means to cooperate in locking engagement with said carrier means and having a notch in its outer edge, and a movable dog on the carrier adjacent to each pocket for engaging in said notch to prevent rotation of the ring while in its pocket.

80

25. In a grinding machine of the type in which piston rings or the like are successively presented to the grinding wheel, an intermittently rotatable carrier having a plurality of interiorly threaded circular pockets for receiving the rings, exteriorly threaded annular locating rings in said pockets, and means to prevent rotation of said locating rings when in said pockets.

95

26. A grinding machine having, in combination, a grinding wheel, an intermittently movable piston ring carrier having a circular interiorly threaded ring holding pocket, an annular exteriorly threaded locating ring adapted to be screwed into said pocket whereby the locating ring is readily replaceable by one of another interior diameter, means for successively supplying said pocket with piston rings, and means driving the carrier to successively transfer said rings to the grinding wheel.

100

27. A grinding machine having, in combination, a work holder, a rotary spindle supporting a work carrier, means for supplying said carrier with articles to be ground, a reciprocating tool head carrying a grinding tool, and a fluid pressure system operative to reciprocate the tool head and to index the spindle step by step to successively deliver the articles to the work holder in timed relation to the movements of said tool.

115

28. A grinding machine having, in combination, a work holder, a rotary spindle supporting a work carrier, means for supplying said carrier with articles to be ground, a reciprocating tool head carrying a grinding tool, two fluid pressure cylinders with double acting pistons having their piston

120

130

- rods operatively connected respectively to the tool head and the spindle to operate them, means for supplying fluid under pressure to one cylinder for moving one of said parts and mechanism operated by the movement of said part for controlling the supply of fluid to the other cylinder.
29. A grinding machine having, in combination, a work holder, a rotary spindle supporting a work carrier, means for supplying said carrier with articles to be ground, a reciprocatory tool head carrying a grinding tool, two fluid pressure cylinders with double acting pistons having their piston rods operatively connected respectively to the tool head and the spindle to operate them, means for supplying fluid under pressure to the cylinder having its piston connected to the tool head, mechanism operated by the movement imparted to the tool head for controlling the supply of fluid to the cylinder having its piston connected to the spindle, and means for causing each alternate stroke of said last named piston to be idle with respect to said spindle rotation.
30. A grinding machine having, in combination, a work holder, a movable work carrier for presenting articles to the work holder, a reciprocatory grinding tool, and fluid pressure mechanism for reciprocating the tool and moving the work carrier.
31. A grinding machine having, in combination, a work holder, a movable work carrier for presenting articles to the work holder, a reciprocatory grinding tool, fluid pressure mechanism for reciprocating the tool and operating the work carrier, the time of operation of the latter being controlled by the movement of the tool.
32. A grinding machine having, in combination, a rotatable work carrier, a reciprocating grinding tool, a fluid pressure work carrier indexing mechanism, and an actuator for said mechanism controlled by the reciprocations of said tool.
33. A grinding machine having, in combination, a work holder, an intermittently movable work carrier and connected operating mechanism therefor, and means for adjusting the vertical position of the carrier and attached parts relative to the holder.
34. A grinding machine having, in combination, a work holder, an intermittently movable work carrier for transferring articles to the holder, fluid pressure oper- ating mechanism for operating the carrier, and means for adjustably sustaining said carrier and mechanism relative to the holder.
35. A grinding machine having, in combination, a work holder, a rotatable work carrier, a work carrier spindle with an attached ratchet and cooperating pawl, fluid pressure mechanism for operating said pawl, a single bracket for sustaining said carrier and its operating mechanism, and means for adjusting said bracket vertically relative to the work holder.
36. In a grinding machine of the type in which the articles to be ground are supplied to a carrier which transfers them to the grinding wheel, a magazine adjacent said carrier for containing a stack of said articles comprising a plurality of side bars, holders for said bars, and means permitting a relative adjustment of the holders to vary the area of the space circumscribed by said bars.
37. In a grinding machine of the type in which the articles to be ground are supplied to a carrier which transfers them to the grinding wheel, a magazine adjacent said carrier for containing a stack of said articles comprising a plurality of brackets presenting vertical bores, and a bar adjustably held in each of said bores whereby the movement of projection of said bars below the brackets may be varied.
38. In a grinding machine of the type in which the articles to be ground are supplied to a pocketed intermittently driven carrier which transfers them to a grinding wheel, a magazine located above the path of travel of said pockets comprising a plurality of spaced side bars constructed and mounted for adjustment toward and from said carrier.
39. In a machine for grinding piston rings and the like, the combination of a grinding wheel, a magnetic chuck for holding articles of work in position for the operation thereon of said wheel, a carrier made of non-magnetic metal and having a recess therein to receive an article to be ground, said carrier being movable to present said article to said chuck, and a bushing for said recess made of a metal substantially harder than that of which the carrier is made, said bushing being removably supported in said recess.

WILLIAM ARTER.
